CAN CLOSURE APPLYING TOOL

George E. Nelson, Chicago, Ill., assignor to Continental Can Company, Inc., New York, N. Y., a corporation of New York

Application January 9, 1939, Serial No. 250,074

1 Claim. (Cl. 113—30)

The present invention relates to new and useful improvements in a device for closing containers, and more particularly to improvements in a tool for applying a closure or sealing member of relatively soft or thin metal to a metal container.

In the co-pending application of George A. Benson, Ser. No. 239,402, filed November 7, 1938, there is shown and described an inner seal or closure member for a metal container of the type including a neck portion. The closure is inserted within the neck portion of the container and is expanded beneath an inwardly curled edge on the neck portion. Such a closure provides an efficient seal with the inner surface of the neck portion for closing the container and is effective to prevent opening of the container without destruction or deformation of the closure, thus guarding against unauthorized tampering with the contents of the container. The present invention more specifically relates to a hand operated tool for applying such a closure to a container of the type shown in the above-mentioned application.

An object of the present invention is to provide a closing tool which will uniformly expand the closure member into continuous and uniform contact with the neck portion of the container, thus insuring a uniform surface contact between the closure and the neck portion of the container.

A further object of the invention is to provide a closing tool of the above type which may be expanded into uniform and continuous contact with the surface of the closure member entirely around the inner surface thereof so as to effect a uniform expansion of the closure member into continuous contact with the neck portion of the container.

A still further object of the invention is to provide a closing tool of the above type which includes a resilient and expandable member and a pair of relatively movable parts for effecting compression of the resilient member and resultant outward expansion thereof whereby to effect a continuous and uniform contact between the closure member and the neck portion of the container.

The invention still further aims to provide a closing tool of the above type which is of simple construction, easily operated and thoroughly efficient in use.

The above and other objects of the invention

will in part be obvious and will be hereinafter more fully pointed out.

In the accompanying drawing:

Figure 1 is a side elevation of the closing tool before the parts thereof are moved to a position for expanding the closure into contact with the container.

Figure 2 is an enlarged fragmentary side view, in section, showing the closing tool after the parts thereof have been moved to a position for expanding the closure into contact with the container.

Figure 3 is a further enlarged fragmentary view in section, showing the position of the tool when inserting the closure into the container.

Figure 4 is a view, similar to Figure 3, showing the position of the tool when expanding the closure into sealing contact with the container.

Referring more in detail to the accompanying drawing, and particularly to Figures 1 and 2 thereof, the tool is illustrated as including a central stem or spindle 10 which is provided with an outwardly extending annular radial flange 11 at the lower end thereof. A sleeve member 12 is provided with a central bore through which the lower portion of the stem 10 is adapted to extend. The sleeve member 12 and the stem 10 are mounted for axial movement relative to one another. The lower end of the sleeve 12 is enlarged to provide an annular portion 13 which is opposed to and substantially co-extensive with the flange 11 on the stem 10. Thus, the opposed surfaces of the flange 11 and the end portion 13 of the sleeve 12 provide an annular recess therebetween. Within this annular recess, a resilient expansible member 14 is disposed. The member 14 is preferably of a suitable rubber composition which is substantially non-compressible, deformable and elastic so that it can be expanded and so that the inherent elasticity or resiliency thereof will cause it to return to a normal position. This member 14 is in the form of an annulus completely filling the space provided between the end portion 13 of the sleeve and the flange 11 on the stem. The resilient member 14 serves, in a manner to be hereinafter more fully pointed out, as a closure expanding or forming member.

The upper end of the sleeve 12 is provided with an outwardly extending radial flange 15, the upper surface of which is adapted to cooperate with cam means for effecting expansion of the resilient member 14 in a manner to be herein-after more fully pointed out. Adjacent the lower

end of the sleeve 12, there is provided an outwardly extending shoulder 16 which is disposed above the end portion 13.

A block 17 is provided with a central bore through which the stem 10 extends. This block 17 is disposed above the sleeve 12 and is provided with outwardly extending pairs of lugs 18, 18a which are disposed above the flange 15 on the sleeve 12. Pins 19, 19a extend through the lugs 18, 18a, respectively, and serve to support operating members 20, 20a. The upper end of the stem 10 is threaded for threadedly receiving an adjusting nut 31 which is provided with a depending flange or skirt 32 against which the block 17 is adapted to abut. A locking nut 33 also threadedly engages this end of the stem 10. The block 17 is thus mounted for limited movement on the stem between the flange 22 on the nut 31 and the flange 15 on the sleeve 12.

The operating members 20, 20a are in the form of bars which, as indicated above, are pivotally mounted on the pins 19, 19a, respectively. Handle brackets 21, 21a are secured by rivets 22, 22a or the like to the bars 20, 20a, respectively. Between the free ends of the handle brackets 21, 21a, handle members 23, 23a are mounted. The ends of the bars 20, 20a are shaped to provide cam surfaces 24, 24a, respectively. These cam surfaces cooperate with the upper face of the flange 15 on the sleeve 12 to effect relative movement between the stem 10 and the sleeve 12. The cam surfaces 24, 24a are shaped to provide stop surfaces 24b which engage the outer surfaces of the block 17 within the lugs 18, 18a to limit downward movement of the handles.

The tool is particularly adapted to be used for applying a closure to a container of the type shown in the co-pending application of George A. Benson, referred to above. As shown in Figures 3 and 4, the container (not shown) is provided with a neck portion 25 which is provided with inwardly extending projections 26 below the open end thereof. Above the projections 26, the neck portion 25 is flared outwardly, as at 27, and is then flared inwardly, as at 28. The free edge around the open end of the neck portion is curled inwardly, as at 29, to provide an inward bead. The closure or inner sealing member is made of relatively soft or thin metal and includes a bottom wall portion 30 and an upstanding peripheral wall portion 30a.

After the container has been filled with its contents, the closure member is placed over the flanged end of the tool stem 10 and is then inserted within the neck portion of the container, as shown in Figure 3. The peripheral wall portion 30a of the closure member surrounds the forming or expanding member 14 and the bottom wall 30 of the closure member is positioned against the inward projections 26. In this position of the closing tool, with the flange 11 and the end 13 of the sleeve 12 normally separated, the resilient expanding member 14 completely fills the space therebetween and the outer surface thereof is in line with the outer edges of the flange 11 and the end portion 13. The shoulder 16 on the sleeve 12 abuts against beaded edge 29 of the neck portion of the container so as to limit inward movement of the tool relative to the container.

When it is desired to expand the closure member into sealing contact with the inner surface of the neck portion of the container, the operating members 20, 20a are moved from a substantially vertical position, as shown in Figure 1,

to a substantially horizontal position, as shown in Figure 2. This movement of the operating bars 20, 20a will bring the cam surfaces 24, 24a into engagement with the flange 15 on the sleeve 12 and will cause the block 17 to abut against the edge of the flange 32 on the adjusting nut 31. Thus, the cam surfaces 24, 24a in moving with the operating bars 20, 20a to the position of Figure 2, will cause relative movement between the stem 10 and the sleeve 12 so that the end portion 13 on the sleeve and the flange 11 on the stem will approach one another. This movement of the stem and sleeve will reduce the size of the annular recess provided between the flange 11 and the end portion 13 so that the resilient forming member 14 will be compressed. In tending to compress the forming member 14, this forming member will be expanded outwardly beyond the edges of the end portion 13 and the flange 11, as shown in Figures 2 and 4. As more particularly shown in Figure 4, this outward expansion of the forming member 14 will force the peripheral wall portion 30a of the closure member beneath the beaded edge 29 on the container and into surface contact with the inner face of the neck portion above the projections 26. The forming member 14 is uniformly expanded entirely around the same so that a continuous and uniform expansion of the wall portion of the closure member is effected. Thus, a continuous and uniform sealing contact is afforded between the closure member and the neck portion of the container. By shifting the operating bars 20, 20a to the substantially vertical position shown in Figure 1, the inherent resiliency of the forming member 14 will cause the same to assume the normal position thereof, as shown in Figures 3 and 4, so that the tool can be removed from within the neck portion of the container.

From the construction described above, it will be apparent that compression of the rubber washer or forming member 14 can be adjusted by means of the nut 31. Thus, the downward movement of the nut 31 relative to the spindle 10 will reduce the permissive movement of the block 17 relative to the spindle, and consequently the end 13 of the sleeve 12 and the flange 11 on the spindle 10 can be brought closer together by the cam means 24, 24a. The locking nut 33 is for maintaining the adjusting nut 31 in its adjusted position.

From the foregoing description, it will be seen that there is provided a tool for providing a can closure which is adapted to be expanded into contact with the container. The tool is one which effects a uniform and continuous expansion of the closure member so that a continuous sealing contact is afforded between the closure member and the container. While one form of the invention has been shown for purposes of illustration, it is to be clearly understood that minor changes in the details of construction and arrangement of parts may be made without departing from the scope of the invention as set forth in the appended claim.

I claim:

A tool for applying an inner closure to a container comprising a stem with a radial flange at one end thereof, a sleeve member surrounding said stem and having one end thereof opposed to and substantially co-extensive with said radial flange, a substantially non-compressible but deformable elastic forming member disposed between the end of said sleeve member and said radial flange and normally co-extensive with the

outer edges thereof, a block member loosely mounted on said stem above the opposite end of said sleeve member and having laterally extending pairs of lugs, adjusting means on the opposite end of said stem for limiting upward movement of said block member relative to the stem, cam elements pivotally mounted between said lugs and having cam surfaces engageable with said sleeve member for effecting relative movement between said stem and said sleeve member with the radial flange and the adjacent end of said sleeve member moving toward one another whereby to outwardly force said forming member into expanding contact with the wall of the

inner closure, said cam elements having stop surfaces engageable in a radial direction with the outer surface of said block member between the said lugs whereby to limit relative movement between said stem and said sleeve member, and means providing an outwardly extending peripheral shoulder on said sleeve member and said shoulder being spaced slightly above said forming member and above the wall of the inner closure and adapted to contact with the edge of the container whereby to limit movement of the tool and the closure relative to the container during insertion and expansion of the closure.

GEORGE E. NELSON.
